UNITED STATES PATENT OFFICE.

DUGALD S. PATERSON, OF PHILADELPHIA, PENNSYLVANIA.

SHEET-PACKING.

1,160,316.

Specification of Letters Patent. Patented Nov. 16, 1915.

Application filed September 16, 1914. Serial No. 861,990.

To all whom it may concern:

Be it known that I, DUGALD S. PATERSON, a citizen of the United States, residing in the city and county of Philadelphia, State 5 of Pennsylvania, have invented a new and useful Sheet-Pack, of which the following is a specification.

My invention consists of sheet packing composed of a body of metal and fibrous material thereon, it being adapted to be cut into shapes as gaskets and for other purposes.

The invention is satisfactorily illustrated in the accompanying drawing, but the important instrumentalities thereof may be varied, and so it is to be understood that the invention is not limited to the specific details shown and described.

Figure 1 represents a face view of a sheet packing partly broken away embodying my invention. Fig. 2 represents a longitudinal section thereof on the line α — α Fig. 1, on an enlarged scale. Fig. 3 represents a face view similar to Fig. 1 of another embodiment of the invention. Fig. 4 represents a perspective view of another embodiment of the invention.

Similar numerals of reference indicate corresponding parts in the figures.

Referring to the drawings, 1 designates a piece of sheet metal which is struck up, pressed, or bent into depressions and elevations at intervals forming in the opposite faces thereof the pockets 2 and composing the body of the packing. On said faces of the body is placed a covering 3 of asbestos or other suitable fibrous material, said covering occupying and filling said pockets and extending over the outer walls of the elevated portions of the pockets forming continuous surfaces of the coating material on both faces or sides of the body.

In some cases, it is desirable to have the pockets open at the top and bottom, as in Fig. 3, in which case the piece 4 of expanded-metal will answer admirably for the purpose, the fibrous material 3 filling such pockets throughout end to end and joining the material that forms the entire covering

of said piece. In other cases, it is desirable to fill the pockets with the fibrous material 50 and leave uncovered the bases 5 of said pockets which may be above or below, so that said bases and material alternate, producing a checker-board effect, as shown in Fig. 4. 55

The packing will be found adapted admirably to be formed into gaskets for various purposes, brake band linings of auto vehicles, treads or pads for foot boards, stairs, etc., and other articles and shapes. 60

Having thus described my invention what I claim as new and desire to secure by Letters Patent, is:—

1. A sheet packing comprising bent metal sheet forming pockets, and fibrous packing 65 in the pockets, substantially as described.

2. A sheet packing comprising a bent metal sheet having fibrous material embedded in the surface thereof, substantially as described.

3. A sheet packing comprising a bent metal sheet having pockets in its opposite faces, and fibrous material in said pockets, substantially as described.

4. A sheet packing comprising a bent 75 metal sheet having fiber containing pockets therein, and the walls of said pockets bent at an angle to the surfaces of the packing of the sheet, substantially as described.

5. A sheet packing comprising a bent 80 sheet of metal having pockets formed in its opposite faces, fibrous material in said pockets, and the walls of said pockets bent at an angle to the surface of the packing, substantially as described.

6. A sheet packing comprising a section 85 of sheet metal bent forming pockets in both faces of the sheet, said pockets separated from each other, and fibrous packing in said pockets lying flush with the surfaces of the metal sheet, substantially as described.

DUGALD S. PATERSON.
